FLUENT MATERIAL DISPENSER AND SPREADER

Robert W. Turner, Port Jefferson, Ohio

Application September 26, 1949, Serial No. 117,807

4 Claims. (Cl. 91—25)

1

This invention relates to novel and useful improvements in fluent material dispensers and applicators.

An object of this invention is to dispense a controlled quantity of fluent material, as asphalt, tar, or mixtures thereof employed in the preparation of roofs, from a discharge end of a hopper which is controlled by a valve, the valve having a link secured thereto with a spring reacting on the link and the base which supports the hopper so as to resiliently oppose the operation of the link and to resiliently press the valve in the outlet closing position, and to discharge the fluent material during oscillation of the hopper, which is pivotally carried by the base.

Another object of this invention is to effectively spread the material by causing it to be acted upon by brush assemblies, the brush assemblies consisting of a number of rotary brushes which have flanking stationary brushes, all of the brushes being suspended from the bottom of the base.

Another object of this invention is to improve the valve operation by a linkage assembly to actuate said link, which linkage assembly includes a member which is secured to said link and which has a flexible cable or the like secured thereto, which cable extends around the drum which is to be turned manually for displacing the link against the biasing force of the spring.

Ancillary objects and features will become apparent in following the description of the illustrated form of the invention.

In the drawings:

Figure 1 is a plan view of the device.

Figure 2 is an elevational view of the device shown in Figure 1, with portions being broken away to illustrate the detail of construction;

Figure 3 is a sectional view of a part of the device shown in Figure 1;

Figure 4 is a bottom view taken substantially on the line 4—4 of Figure 2 and in the direction of the arrows, showing the brush assembly;

Figure 5 is an elevational view of the device illustrating particularly the operation of the valve and its actuation assembly;

Figure 6 is a horizontal sectional view of a part of the device to show the manual transmission actuation control, and;

Figure 7 is a view taken substantially on the line 7—7 of Figure 3 and in the direction of the arrows, showing the heater and valve, portions of the other structure being removed.

This invention has a field of utility similar to

2

that described in my co-pending application Serial No. 47,025, which was filed on August 31, 1948, now Patent No. 2,517,057.

The hopper 10 is adapted to maintain a supply of fluent material widely used in repairing or originally installing asphalt roofing. The material employed is fluent when maintained above a temperature higher than normally found as climatic.

10 The hopper has a pair of sides with pivot pins 12 and 14 secured thereto. The hopper has an inlet 16 and a discharge opening or outlet 18.

15 A heater consisting of heating elements disposed in cases 20 and 22, is secured to the hopper 10 adjacent the outlet 18. Accordingly, while the heater is operative, the heat is applied to the hopper at the most essential place, namely the discharge opening region. Conventional circuit breaker type control is employed for operation of the heater.

20 The hopper is passed through an opening in a base generally indicated at 24. This base consists of structural members of known description. A pair of wheels 26 and 28 are disposed on an axle 30 at one end of the base. A support is formed in two parts and secured to the base. Each part consists of structural members connected together by means of bolts, welding, riveting or the like. The almost vertical structural member 29 has its lower end secured to the base and its upper end secured to a substantially horizontal structural member 30. The structural member 30 is secured at its other end to the axle 32. The connecting cross member 34 is secured to the base (see Figure 6) and also to the substantially horizontal structural members 30. Upstanding portions 36 and 38 of the cross member also form a part of the support. The upper ends of the upstanding portions are secured to the structural framing members 40 and 41 which are legs of the U-shaped member 42. This U-shaped member has bearings 44 and 46 secured to its web accommodating the shaft 48.

25 The shaft 48 has a knob 50 at one end thereof and a drum 52 secured adjacent the knob. The drum has a flexible member, such as a cable 54, secured at one end thereto and at the other end to the upturned end of a bar 56. The down-turned opposite end of the bar has a spring 58 secured thereto which is also secured to a part of said support.

30 The shaft 48 has a knob 50 at one end thereof and a drum 52 secured adjacent the knob. The drum has a flexible member, such as a cable 54, secured at one end thereto and at the other end to the upturned end of a bar 56. The down-turned opposite end of the bar has a spring 58 secured thereto which is also secured to a part of said support.

A valve 60 consisting of a plate having angularly connected sections is secured to the hopper by means of a hinge 62. The valve is disposed over the outlet 18 for control thereof. A link

(Figures 5 and 7) 64 has its lower transverse end secured in bearings 66 and 68 which are secured to the valve 60. The substantially straight portion 64 has its upper end adjustably secured to the bar or rod 56 intermediate the curved ends thereof. A pair of nuts are employed to adjustably connect the link 64 to the member 56, one nut being disposed on opposite surfaces of the member 56 so that they are employed to lock the link in place.

From the foregoing, operation of the valve is summarized as follows: rotation of the shaft 48 by the knob 50 causes the cable 54 to be wound on the drum 52. This displaces the member 56, pulling it against the opposing force of the spring 58 which is employed normally to maintain the link 64 in one position, that is, the valve closing position. There is sufficient friction in the bearings to hold the valve 60 in the selected adjusted position.

A motor 70 is disposed on the base and has a shaft projecting therethrough. This shaft has a double sheave, consisting of pulleys 74 and 76 fixed thereto, below the undersurface of the base 24. A counter shaft 78 is mounted in a suitable bearing and carried by the base. This counter shaft is rotated by the motor 70 through a transmission consisting of the pulley 76 and a pulley 80, with a belt 82 entrained around both of these pulleys. The bearing in which the shaft 78 rotates is on a swinging arm 84 which is pivoted to the base 24. Upon operation of the swinging arm 84, the belt 82 is selectively tightened and allowed to slip, whereby the control of the transmission operativeness is attained. The swinging arm 84 is passed through an opening 86 (Figure 5) formed in the base 24 having a number of teeth 88 extending therein. These teeth are engaged by the dog 90 which is fixed to the swinging arm 84 so that selected pivoted positions of the arm 84 may be attained and kept.

An eccentric 92 (Figure 3) is secured to the pulley 80 and a pitman 94 is secured to the eccentric. The pitman is also secured to a hanger 96 which is carried by the hopper whereby upon operation of the motor, the transmission transfers the torque of said motor to oscillatory movement of the hopper about the pivot pin 12 and 14 as an axis.

A handle 98 is secured to the base appropriately to manually operate the device.

A brush assembly is disposed at the end of the base opposite from the wheel 26 and 28. This brush assembly consists of a spreader brush 100 which is fixed stationary on a mounted assembly 102. This assembly includes a plate which is bolted to the base and sufficient cross members to actually support the brushes. The spreader brush 100 is stationary and includes a center section together with angularly disposed end pieces or brushes, 104 and 106. Another stationary brush 108 is secured to the mounting assembly 102 but spaced from the brush 100. The brush 108 is used as a follower brush and is substantially parallel to the brush 100.

A number of brushes 110, 112, 114, 116, 118 and 120 are rotatably mounted on suitable small shafts on the mounting assembly. Each of the rotary brushes has a gear secured thereto and the gears are enmeshed. Accordingly, rotation of one brush causes rotation of all of the others of the rotary brush group.

This rotation is imparted by means of the motor 70. The belt 122 is entrained around the pulley 74 and also around the pulley 124. The

pulley 124 is rotatably mounted on the shaft 126 which is suspended from the bracket 128. This bracket is carried by the base 24.

A pulley 130 is also secured to the shaft 126 and has the belt 132 entrained therearound. This belt is drivingly connected with the pulley 134 which is disposed on the shaft 136. The shaft 136 supports the brush 110 of the rotary group, whereby, upon operation of the motor 70, rotation of all the brushes of the rotary group is obtained.

Having described the invention, what is claimed as new is:

1. A fluent material applicator comprising a base having wheels at one end and a brush assembly at the opposite end, a fluent material supply hopper carried by said base for oscillation and provided with means for oscillating said hopper, a heater disposed adjacent the discharge end of said hopper, a valve disposed at the discharge end of the hopper and having a manual means for actuating the valve, said brush assembly being disposed rearwardly of said hopper and including a plurality of rotary brushes with flanking stationary brushes, said hopper oscillating means including a motor secured to said base and a belt and pulley transmission connecting said motor and said hopper, and means secured to said base and operatively connected with said transmission for manually controlling the operation of the transmission.

2. In a fluent material dispenser and spreader, a base having an opening, a brush assembly disposed at the back end of said base, a motor secured to said base, said brush assembly including a pair of spaced stationary brushes and a plurality of rotary brushes therebetween, a transmission drivingly connecting said motor and said rotary brushes with manually operable means for controlling the actuation of said transmission, a fluent material hopper mounted for oscillation on said base and having a lower discharge end disposed in said opening and located forwardly of said brushes, a valve for said hopper open lower end, a link secured to said valve, and a spring reacting on said base and said link opposing the operation of said link and resiliently biasing said valve to the closed position, and means drivingly connected with said motor and the lower end of said hopper for oscillating said hopper in unison with the rotation of said brushes.

3. A fluent material spreader and dispenser comprising a base with a support extending upwardly therefrom, a hopper having sides and a discharge outlet, means pivoting said sides to said support so that said hopper is mounted on said base for oscillation, a valve secured to said hopper for said outlet, a link secured to said valve and resilient means reacting on said link and said support opposing the operation of said link and maintaining said valve in the closed position, means for overcoming the biasing means to open the valve, a brush assembly secured to and disposed below said base and located rearwardly of and below said outlet, said assembly including a plurality of rotary brushes with at least one stationary brush adjacent thereto, a motor secured to said base, and means including a transmission for connecting said motor with said hopper to oscillate said hopper.

4. In a fluent material spreader which includes a base provided with wheels, said base having an aperture therein, a motor mounted on said base and having a shaft, said shaft being located in part below said base, a support carried by said base, a hopper, means mounting said hopper on

said support for oscillation, said hopper having a lower discharge end located below said base and a part of said hopper being passed through the aperture in said base, said shaft being provided with means for oscillating said hopper, said oscillating means secured to said hopper adjacent to the discharge end thereof and below said base, a valve operatively connected with the discharge end of said hopper to control the size of the discharge opening in the discharge end of said hopper, a brush mounted for movement below said base and carried by said base, and means for actuating said brush connected with said brush and the said means for oscillating said hopper.
